UNITED STATES PATENT OFFICE.

RICHARD E. KRAUSE, OF BROOKLYN, NEW YORK, ASSIGNOR OF ONE-HALF
TO ERNEST J. KALTENBACH, OF BROOKLYN, NEW YORK.

ROTARY EXPLOSIVE-ENGINE.

No. 851,675.

Specification of Letters Patent.

Patented April 30, 1907.

Application filed December 3, 1904. Serial No. 235,314.

To all whom it may concern:

Be it known that I, RICHARD E. KRAUSE, a subject of the King of Sweden, residing at Brooklyn, county of Kings, and State of New York, have invented certain new and useful Improvements in Rotary Explosive-Engines, of which the following is a specification.

This invention relates generally to improvements in rotary engines and specifically to that class known as rotary explosion or internal combustion engines.

The objects of this invention are generally to improve and simplify the construction of engines of this class to increase their efficiency and effect economy in the manufacture thereof.

I will describe a preferred embodiment of my invention and point out the novel features thereof in claims.

In the accompanying drawings, Figure 1 is a side elevation of the engine. Fig. 2 is a section on the line *a—a*, Fig. 1, looking in the direction of the arrow. Fig. 3 is a transverse horizontal section showing the pump and pipes in elevation. Figs. 4 and 5 show modified forms of the piston and admission ports.

In the general construction of the engine, 1 is the base having suitable side supports 2 which are adapted to support the hubs 3 and 4, said hubs respectively forming part of the cylinder 5 and the cylinder head 6. Journaled within these hubs 3 and 4 is the main shaft 8, said shaft having splined thereon within the cylinder 5 a piston 10, as shown in Fig. 3.

The cylinder 5 is preferably constructed in the manner shown in Fig. 3, that is, the circumferential walls and the side walls on one side of said cylinder are formed integral, thereby reducing possibility of leakage. The plate 6 forming the head of the cylinder is bolted thereto in the manner shown in Fig. 1 and has cut therein suitable admission ports which will be hereinafter explained.

In order to keep the working parts as cool as possible and to promote a free circulation of air through the engine I preferably construct the cylinder 5, piston 10 and cylinder head 6 in the manner shown in Figs. 2 and 3, that is, the said parts each have hubs which are journaled on the main shaft 8, but are cut away as shown in Fig. 2 and have respectively arms 11, 12 and 13. Thus it will be

seen that when the engine is in operation 55 air can freely circulate around the piston and cylinder, thereby keeping said parts cooled.

The main portion 14 of the piston 10 is of less diameter than that of the interior of the cylinder and is concentric therewith. 60 The piston is provided with a plurality of piston blades 15 which engage the interior wall of the cylinder. One side of each piston blade 15 presents a face 16 which forms one of the side walls of a combustion chamber 65 17. These faces or walls 16 are almost radial while each of the outer walls 18 of said piston blades is tangential to the portion 14. The object of this construction is to have the walls 16 present a desirable working surface within the combustion chamber, while the outer walls 18 will operate to raise the abutments.

Slidably mounted in openings 22, within the peripheral walls of the cylinder are abutments 23 which are capable of being moved outwardly through the cylinder by means of the walls 18 of the piston blades. These abutments are returned to the position shown in Fig. 2 by means of expansion springs 25, 70 80 mounted on rods 26, said rods being secured to the body of the cylinder in the manner shown in Fig. 2. The abutments 23 are provided with lugs 28 through which rods 26 pass and against which the expansion springs 85 25 rest so that when said abutments are driven out by the piston blades they will be returned by the springs 25 expanding against said lugs.

The exhaust ports 20 are arranged in the 90 manner shown in Figs. 1 and 2, that is, the said ports are placed adjacent to the sliding abutments 23 so that when the piston rotates all the inert gases will be driven out of said cylinder before the abutment is moved from 95 the position shown in Fig. 2. It will be observed that the tangential sides 18 of the piston blades are of sufficient length to overlap an abutment and the adjacent exhaust port. This will prevent any appreciable amount of 100 inert gas being trapped in the short space between the abutment and exhaust port and consequently there will be no back pressure on the piston. By reason of this complete removal of the inert gases from the cylinder prior 105 to the lifting of the abutments it will be observed that when the parts assume the position shown in Fig. 2 the combustion chamber

will be free from all inert gases and capable of receiving a full charge of a perfect mixture, thereby giving the greatest possible efficiency when the explosion occurs.

Projecting through the peripheral walls of the cylinder, into the combustion chamber, in the manner shown in Fig. 3, are the spark plugs 30, which may be of any suitable construction or design, but preferably what is known as a jump spark, the sparking of said plugs being so timed as to occur after the admission ports are closed. Projecting directly into the combustion chambers, also shown in Fig. 3, are relief cocks 31 which are generally used when it is desired to start the engine.

Some means must be provided for supplying the explosive mixture under pressure to the combustion chambers, and it is, of course, desirable that this be done automatically. In the present case I have shown means controlled by the rotation of the piston for governing the admission of the explosive mixture to the combustion chambers, and I have also shown means operated by the shaft 8 for compressing the explosive mixture. I will now describe specifically the preferred means employed for these purposes.

Attached to the side wall of the piston, on one side, in any suitable manner, is a ring 35 which is adapted to ride in a groove 36 cut in the side wall of the cylinder in the manner shown in Fig. 3. This ring overlaps the meeting lines of the walls of the piston and the cylinder and acts as a packing ring to prevent the escape of gases from the cylinder. Secured to the side wall of the piston, on the opposite side, is a circular plate 38 which is of sufficient diameter to ride against the interior wall of the cylinder. This plate 38 is arranged to ride in a groove 39 in the head of the cylinder in the same manner as the ring 35 and also acts as a packing ring between the cylinder head and the piston. This plate has cut therein openings 40 (see Fig. 2) which extend from the top of the piston to the periphery of the plate and are preferably of elongated formation. This plate operates to open and close the admission ports either simultaneously, successively or alternately, as may be desired. In Fig. 2 the plate 38 is shown to simultaneously open the ports diametrically opposite each other so that when an explosion occurs the force of said explosion will be delivered simultaneously against the two opposite sides of the piston, thereby removing the strain on said piston. Secured to the cylinder head 6 in any suitable manner are the gas retaining chambers 43. Leading directly from the gas retaining chambers to the combustion chambers are admission ports 44 similar in shape to the openings 40 in the plate 38. Connected to the gas retaining chambers 43 is a pipe 46, (Figs. 1 and 3),

which is directly connected to a pipe 47, said pipe 47 being connected to the pressure pump 48. The pressure pump 48 also has a pipe 49 which is directly connected to a pipe 50, said pipe conveying the gas directly from the carburetor 51 to said pressure pump. Connected to the pipe 46 and the pipe 49 is a pipe 52 which has therein a valve 53. Located within the pipe 49 is a spring actuated valve 55 which is capable of being opened when the piston 56 of said pump moves downward and which will close when said piston is moved upward. Located within the pipe 47 is a valve 57, similar in construction to valve 55, but operating in an opposite manner, that is, when the piston 56 moves downward said valve 57 will be closed, but when the piston is moved upward the said valve will be opened.

The pressure pump 48 is suitably supported by a bracket 60 forming part of the hub 4 of the cylinder head. Piston 56 is operatively controlled by piston rod 61, said piston rod being journaled to a crank 62, said crank being driven by the driving shaft 8, as shown in Fig. 1. Thus it will be seen, presuming the carburetor to be operating, that the gases will be drawn from the carburetor through the pipe 50 into the pressure pump 48 when the piston 56 moves downward and opens the valve 55. When the piston 56 makes its upward stroke the valve 55 will be closed whereupon the gases will open valve 57 and be forced through pipe 47 to pipe 46 and then enter the gas retaining chambers 43 by which time the circular plate 38 will have brought the openings 40 therein into position to register with the openings 44 in the cylinder head, thereby admitting the gases to the explosion chamber, whereupon the circular plate 38 will continue to rotate and when the parts have assumed the position shown in Fig. 2, that is, so that the openings 40 have passed the opening 44 and the abutments have dropped, an explosion will occur and the piston receives its driving force.

The pressure pump will always take in sufficient gas from the carburetor to give the required pressure within the explosion chambers. The pipe 52 which connects the pipe 46 and pipe 49 may be here termed a shunt pipe and is employed to regulate the pressure of the gases delivered to the combustion chambers. If the valve 53 in pipe 52 is closed the pressure pump 48 will deliver the gases to the cylinder under extreme pressure, but if the valve 53 is opened to any degree which may be desired, more or less of the gases will be permitted to return through pipe 52 and pipe 49 to the pressure pump 48 thereby causing a circulation of the gases between the pump and pipe 46, and reducing the pressure of the gases delivered to the combustion chambers. In order to determine the exact pressure of gases being de-

livered to the combustion chambers I place preferably within the pipe 46 a pressure gage 65

The engine can be started in any suitable manner usually by a handle attached to the shaft. This is a common form used for starting explosion engines and it is not thought necessary to give a description and detail of construction.

10 In Fig. 4 a modification is shown, wherein the openings 40 in the plate 38 and the openings 44 in the cylinder head are arranged in such manner that gases are admitted to the explosion chambers only upon each complete revolution of the piston.

In Fig. 5 another modified form is shown wherein the plate 38 has four openings 40 therein and the cylinder 6 has four openings 44 therein, so that, if desired, gases may be admitted through the four ports in less quantities than delivered into two ports and the explosions may occur simultaneously, alternately or successively.

Of course, it is obvious from the foregoing description that certain parts of detail and modifications in construction may be varied without departing from the spirit of the invention.

The operation of the invention is as follows: Gases are taken from the carbureter through pipe 50 into the pressure pump 48 and from the pressure pump is delivered to pipes 47 and 46 and thence to the gas retaining chambers 43 where it is delivered through the ports 44 into the combustion chambers 17 through the openings 40 in the plate 38. The position shown in Fig. 2 discloses the piston and abutments in position wherein the combustion chambers are formed and after gases have been delivered into said combustion chambers, the explosion then occurs which drives the piston in the direction of the arrow, shown in Fig. 2, causing the walls 18 of the piston to discharge inert gases through the exhausts 20, following which the walls 18 will lift the abutments 23 and allow the piston heads 15 to pass by said abutments, whereupon the abutments will ride down the wall 16 of the piston blade and again assume the position shown in Fig. 2. When the abutments first start to move down the walls 16 of the piston the openings 40 will be approaching the position to register with the openings 44 in the cylinder head, so that just as the abutments have reached the position shown in Fig. 2 the openings 40 and 44 will register with each other and the gases will be admitted to the combustion chambers and when the piston passes to the position shown in Fig. 2 the explosions again occur. When it is desired to diminish the speed or efficiency of the engine the pressure of the gases delivered to the cylinder can be decreased by opening the valve 53 and permitting the gases to return to the

pressure pump through the pipe 52. This opening of the valve 53 will permit a free circulation of the gases in the required quantity between pipe 46 and the pressure pump. Thus it will be seen that the engine can at all times be controlled as to efficiency and speed by varying the pressure of the gases by the valve 53.

Having thus described my invention, what I claim as new therein and desire to secure by Letters Patent is:

1. In a rotary explosive engine, the combination of a stationary cylinder provided with admission ports, a piston rotatably mounted within said cylinder, abutments 80 coöperating with said piston to form combustion chambers, a plate carried by the piston and provided with openings adapted to register with the admission ports in the cylinder after the abutments have been operated to form the combustion chambers, a pressure pump controlled by the engine, pipes connecting said pump with the combustion chambers, a shunt pipe connecting the pump with the pipes leading to the combustion chambers, and a valve in said shunt pipe for controlling the pressure of the gases delivered to the combustion chambers. 85

2. In a rotary explosive engine, the combination of a stationary cylinder provided with admission ports, a piston rotatably mounted within said cylinder, abutments 95 coöperating with said piston to form combustion chambers, a plate carried by the piston and provided with openings adapted 100 to register with the admission ports in the cylinder after the abutments have been operated to form the combustion chambers, a carbureter for generating the gases, a pump controlled by the engine, pipes connecting the pump with the carbureter, and combustion chambers, valves within said pipes permitting the gases to be taken from the carbureter and delivered under pressure to the combustion chambers, and means 105 for varying the degree of pressure of said gases. 110

3. In a rotary explosive engine, the combination of a stationary cylinder provided with admission ports, a piston rotatably 115 mounted within said cylinder, abutments coöperating with said piston to form the combustion chambers, a plate carried by the piston and provided with openings adapted 120 to register with the admission ports in the cylinder after the abutments have been operated to form the combustion chambers, a carbureter for generating the gases, and a pump controlled by the engine for receiving the gases from the carbureter, and delivering 125 them to the combustion chambers under pressure.

4. In a rotary explosive engine, the combination of a stationary cylinder having admission ports on one side thereof, a piston 130

rotatably mounted within said cylinder, and provided with a plate having openings adapted to periodically register with the openings in the cylinder, abutments operatively controlled by the piston and forming one of the walls of the combustion chambers, means for delivering the charges to the admission ports under pressure, and means for exploding said charges within the combustion chambers after the admission ports are closed.

5. In a rotary explosive engine, the combination of a cylinder provided with admission ports, a piston mounted within said cylinder, abutments operatively controlled by the piston to form one of the walls of the combustion chambers, a plate carried by the piston and provided with openings adapted to register with the admission ports in the cylinder and intermittently admit charges to the combustion chambers, means for placing the charges under pressure, pipes for delivering charges to said combustion chambers under pressure, and a valve controlled shunt pipe for varying the pressure of said charges.

6. In a rotary explosive engine, the combination of a stationary cylinder, a piston rotatably mounted within said cylinder, abutments coöperating with said piston to

form combustion chambers, a cylinder head provided with admission ports, a plate carried by the piston and provided with openings adapted to register with the admission ports, after the abutments have been operated to form the combustion chambers, and a sparking device projecting into each of said combustion chambers and timed to become operative immediately after the admission ports are closed.

7. In a rotary explosive engine, the combination of a stationary cylinder provided with admission ports, a piston rotatably mounted within said cylinder, a plate carried by the piston and provided with openings adapted to register with the admission ports in the cylinder, abutments coöperating with the piston to form combustion chambers, means for delivering the gases to said combustion chambers under pressure, means for regulating the pressure of said gases, and a sparking device projecting into each of said combustion chambers and timed to become operative immediately after the admission ports are closed.

RICHARD E. KRAUSE.
